Primary Examiner — Austin Murphy(74) *Attorney, Agent, or Firm* — Michael Best & Friedrich LLP(57) **CLAIM**

The ornamental design for a power tool, as shown and described.

DESCRIPTION

FIG. 1 is a perspective view of a power tool embodying the present disclosure.

FIG. 2 is a front view of the power tool of FIG. 1.

FIG. 3 is a rear view of the power tool of FIG. 1.

FIG. 4 is a first side view of the power tool of FIG. 1.

FIG. 5 is a second side view of the power tool of FIG. 1.

FIG. 6 is a top view of the power tool of FIG. 1; and,

FIG. 7 is a bottom view of the power tool of FIG. 1.

The present application is directed to the shape and contour of the designs illustrated in the drawings. The elements shown in broken lines form no part of the claimed design and are included for the purpose of showing the environment of the claimed design.
